UNITED STATES PATENT OFFICE

2,223,975

ELECTRIC CIRCUIT BREAKER

Oliver C. Traver, Drexel Hill, Pa., assignor to
General Electric Company, a corporation of New
York

Application September 1, 1939, Serial No. 293,085

6 Claims. (Cl. 200—149)

The present invention relates to electric circuit breakers, and more particularly to expulsion type circuit breakers in which the arc is extinguished by gas liberated from the walls of an arc-confining chamber under the action of the arc heat.

In breakers of the gas expulsion type the amount of gas available for extinguishing the arc is dependent upon the arc heat and, as a result, the amount of gas available when the current being interrupted is small is sometimes insufficient to successfully interrupt the arc. If the arc passage is made of sufficiently limited area to create an effective arc-extinguishing gas pressure by the small amount of gas liberated when a light current arc is drawn, destructive pressures will be built up in the restricted arc-confining passage when a heavy current arc is drawn. This characteristic of breakers of this type often prevents their use where a wide range of currents must be interrupted. It is accordingly an important object of the invention to provide an improved construction and arrangement in circuit breakers of the above type which is effective to interrupt currents of widely varying magnitude.

Further objects and advantages of the present invention will become apparent as the following description proceeds, reference being had to the accompanying drawing in which Fig. 1 is an elevational view in section of a circuit breaker embodying the invention; Fig. 2 is a sectional view taken along the line 2—2 of Fig. 1, and Fig. 3 is an elevational view of a modification thereof.

Referring to Fig. 1, I have shown my invention embodied in a circuit breaker comprising an arc-confining structure 10 in the form of an elongated tube of insulating material. The tube 10 is connected to a supporting insulator 11 by a two-part housing 12 of conducting material. The tube 10 is provided with a lining of gas-emitting material which, in the present case, is in the form of a removable liner 13 which is recessed at its upper end to receive a fixed contact 14. The liner is secured in the tube 10 by a threaded member 14a which engages the lower end of the tube. The contact 14 is annular in shape and formed of a plurality of spring-biased segments. The contact is connected to the housing 12 in any suitable manner as by the conducting strips 15 which are clamped between the upper part of the housing and an annular washer 16 of insulating material. The washer is received between the two parts of the housing at its outer edge and extends inwardly to form a header against which 55 the arc-confining tube 10, the liner 13 and the

stationary contact 14 are pressed when the switch is assembled.

The movable contact of the switch is in the form of an elongated hollow rod 17 having an extension or pencil 18 of insulating material secured to the inner end thereof in any suitable manner as by the screw-threaded connection illustrated. The movable contact 17 is arranged to engage the fixed contact 14 in the closed circuit position of the circuit breaker to complete a circuit from the conducting housing which may serve as one terminal of the breaker to the other terminal of the breaker by a suitable sleeve contact (not shown). The movable contact is reciprocated in the arc-confining tube 10 by any suitable mechanism (not shown) in a manner well understood by those skilled in the art.

As the movable contact 17 is withdrawn from the fixed contact during the circuit-interrupting operation of the breaker, the pencil 18 is drawn into the passage in the arc-confining tube 10 defined by the liner 13. In accordance with the present invention the movable contact and the filler pencil 18 are made as nearly the size of the passage through the liner 13 as possible without causing undesirable friction between the relatively movable parts, so that there is very little space between the inner wall of the liner 13 and the outer surface of the movable contact. In order to provide arc-confining passages, the filler pencil 18 is provided with a plurality of grooves 19 which extend generally in the direction of the relative movement between the fixed and movable contacts. The grooves 19 are connected together by a passage 20 formed on the surface of the pencil 18 and extending sufficiently around the same to form a header for the grooves 19. The passage 20 is preferably formed adjacent the inner end of the movable contact 17 where it is in communication with a root of the arc and will be effective to distribute the current of a heavy current arc among the grooves 19 in a manner which will be more fully set out at a later point in the specification.

In some applications it is desirable to provide an arc passage of increasing cross-sectional area as the contacts are separated, in order to provide a larger space for the heated gases and to prevent too great an increase in pressure. This desirable feature may be incorporated readily in the present construction by simply increasing the cross-section of the grooves 19 as they approach the end of the pencil. This is a simple operation from a manufacturing standpoint and permits the construction of a switch having an 55

arc-confining passage of progressively varying cross-section without appreciably increasing the expense of manufacture. In other applications it may be desirable to decrease the cross-sectional area of the arc-confining passage as the separation of the relatively movable contacts increases in order to provide a snuffing action on the arc. For such installations the grooves 19 may be formed with gradually decreasing cross-section 10 as the distance from the movable contact increases. Such a construction is particularly adapted for use in breakers handling relatively small currents where the quantity of arc-extinguishing gas liberated is small and the snuffing 15 action of the tapered arc-confining passage aids in increasing the pressure of the gas available for extinguishing the arc.

In the arrangement shown the arc-confining tube 10 and the liner 13 are provided with intermediate passages 21 which communicate with the interior of an expansion chamber 22 secured to the exterior of the arc-confining tube 10 in any suitable manner as by the screw-threaded connection illustrated in the drawing. The ex-

25 pansion chamber which permits the highly heated and ionized gases exhausted from the arc-confining chamber to expand and cool before they are exhausted into the surrounding atmosphere is, as illustrated in the drawing, divided into upper and lower expansion chambers 23 and 24 by a transversely extending partition 25 having openings 26 formed therein. Suitable mufflers 27 in the form of wire mesh are provided in each of the expansion 30 chambers to deaden the sound of the arc and to aid in cooling and removing the metal vapor or particles from the hot gases before they are exhausted to the atmosphere through openings 28 formed in the outer wall of the chamber 22.

35 40 The advantages of the structure described above will be better understood from a consideration of the circuit-interrupting operation of a breaker in which it is embodied. With the contacts of the breaker in their closed circuit position, as illustrated, a circuit is completed from the housing 12, through the strip 15, the fixed contact 14, the movable contact 17, to the other terminal of the breaker (not shown). When the movable contact is moved downwardly to separate it from the contact 14 the pencil 18 is drawn into the interior of the arc-confining tube 10 and an arc is drawn between the relatively movable contacts. As previously pointed out, the interior of the lining of the arc-confining tube 45 conforms closely in size with the outer surface of the movable contact 17 and the filler pencil 18 attached thereto so that the arc, when drawn, is confined within one of the grooves 19. If the current is small, the gas liberated from the walls 50 of the groove and the liner 13 is small and the resulting pressure, while not great, is sufficient to extinguish the arc confined in the single groove. As the contact 17 is withdrawn from the arc-confining tube the gases liberated by the 55 arc are exhausted through the passages 21 into the expansion chambers 23 and 24 and into the atmosphere through the passages 28. When the movable contact is completely withdrawn from the arc-confining tube the gases may also ex- 60 70 haust directly from the lower end of the tube.

If a large current is being interrupted the arc drawn in one of the passages 19 liberates larger amounts of arc-extinguishing gas because of the greater arc heat. The provision of the passage 75 20 for connecting the grooves 19 together pro-

vides means for transferring the gases from one groove to the other and for dividing the arc into a plurality of parallel branches. Placing the passage 20 adjacent the end of the movable contact at which the arc is drawn renders it very effective to cause a division of the arc when the current is large. The splitting of the heavy current arcs by the structure described above may be understood from a consideration of the voltage current characteristics of a closely confined electric arc. When an arc is unconfined the arc voltage decreases with an increase in current and, under such circumstances, a division of the arc would not occur. However, when an arc is closely confined, as with the present construction, the voltage drop across the arc increases with the current flow after a certain current level is reached and, under these circumstances, the arc will seek a parallel path and a divided arc will be maintained whenever it can be established with a lesser voltage gradient than that required to maintain the total arc current in a single groove.

Thus, it is seen that the present construction provides a circuit breaker having a plurality of 25 arc-confining passages electrically in parallel and adapted to be brought into use automatically by the conditions created in the arc-confining structure by the arc itself. As a result, the conditions existing in any one of the arc-confining grooves 30 19 vary over a relatively small range as compared with the range of currents being interrupted since any increase in current value beyond a certain point will cause a division of the arc among two or more of the grooves. This 35 action results in more uniform interrupting characteristics and, at the same time, increases the range of currents which may be interrupted by the breaker.

In Fig. 3 I have shown a filler pencil 30 which 40 may be substituted for the pencil 18 shown in Fig. 1. In accordance with the modification illustrated in this figure a plurality of spiral grooves 31 are provided in the surface of the pencil 30 and are connected together at their lower ends by a connecting passage 32. The use 45 of spiral arc-confining grooves in the filler pencil increases the length of the arc for a given movement of separation of the relatively movable contacts and adapts the switch for operation 50 in higher voltage circuits without proportionately increasing its physical dimensions.

What I claim as new and desire to secure by Letters Patent of the United States, is:

1. An electric circuit breaker of the expulsion type comprising means defining an arc passage, a fixed contact, a movable contact engaging said fixed contact in the closed circuit position of said breaker and separable therefrom to draw an arc in said passage and a member of insulating material movable into said passage upon circuit-interrupting operation of said breaker, the walls of said arc-confining passage and said insulating member being closely fitting and gas emitting under the action of the arc and shaped to provide a plurality of interconnected grooves extending generally in the direction of separating movement of said contacts and providing a plurality of arc-confining passages.

2. An electric circuit breaker comprising means defining an elongated passage, a stationary contact, a movable contact extending into said passage and engaging said fixed contact in the closed circuit position of said breaker, a member of insulating material connected to said movable con- 75

tact and movable therewith into said passage when said movable contact is moved toward circuit-interrupting position, the cooperating surfaces of said member and the walls of said passage having a plurality of interconnected grooves formed thereon to provide a plurality of arc-confining passages.

5. An electric circuit breaker of the gas expulsion type, comprising means defining an elongated arc-confining chamber, a fixed contact, a movable contact movable in and closely fitting said arc-confining passage, an extension of gas-emitting material on said movable contact arranged to be drawn into said arc-confining passage upon separating movement of said fixed and movable contacts, said extension being provided with a plurality of grooves extending generally in the direction of separating movement of said contacts and a passage communicating with said grooves adjacent the end of said movable contact and providing for the free transfer of arc gases from one groove to another and a division of the arc among the grooves in accordance with the magnitude of the arc current.

10. An electric circuit breaker of the gas expulsion type comprising means defining an elongated passage, a stationary contact, a movable contact extending into said passage and engaging said fixed contact in the closed circuit position of said breaker, a member of insulating material connected to said movable contact and movable therewith into said passage when said movable contact is moved toward circuit-interrupting position, the cooperating surfaces of said member

15. An electric circuit breaker of the gas expulsion type, comprising means defining an elongated arc-confining chamber, a fixed contact, a movable contact movable in and closely fitting the walls of said arc-confining chamber, an extension of insulating material on said movable contact arranged to be drawn into said arc-confining chamber upon separating movement of said fixed and movable contacts, said extension being provided with a plurality of spiral grooves extending generally in the direction of separating movement of said contacts and a passage communicating with said grooves adjacent the end of said movable contact and providing for the free transfer of gas from one groove to another.

20. An electric circuit breaker of the gas expulsion type comprising means defining an elongated passage, a stationary contact, a movable contact extending into said passage and engaging said fixed contact in the closed circuit position of said breaker, a member of insulating material connected to said movable contact and movable therewith into said passage when said movable contact is moved toward circuit-interrupting position, the cooperating surfaces of said member and the walls of said passage being shaped to provide a plurality of interconnected arc-confining passages having a cross-sectional area varying progressively with the separation of said fixed and movable contacts.

25. An electric circuit breaker of the gas expulsion type comprising means defining an elongated passage, a stationary contact, a movable contact extending into said passage and engaging said fixed contact in the closed circuit position of said breaker, a member of insulating material connected to said movable contact and movable therewith into said passage when said movable contact is moved toward circuit-interrupting position, the cooperating surfaces of said member and the walls of said passage being shaped to provide a plurality of interconnected arc-confining passages having a cross-sectional area varying progressively with the separation of said fixed and movable contacts.
